UNITED STATES PATENT OFFICE.

EDWARD E. JENKINS, OF FLORA, ILLINOIS.

MOUNTING FOR CALCULATING-WEBs AND THE LIKE.

1,194,390.

Specification of Letters Patent. Patented Aug. 15, 1916.

Application filed August 8, 1913. Serial No. 783,784.

To all whom it may concern:

Be it known that I, EDWARD E. JENKINS, a citizen of the United States, residing at Flora, in the county of Clay, State of Illinois, have invented certain new and useful Improvements in Mountings for Calculating-Webs and the like; and I do hereby declare the following to be a full, clear, and exact description of the invention, such as will enable others skilled in the art to which it appertains to make and use the same.

The present invention is directed to improvements in calculators, and more particularly to those employing webs on which the results of calculations are marked.

The invention has for its object to so construct a device of this character that it may be easily and quickly manipulated so that a given amount may be computed and the answer read at a glance.

A further object of the invention is to provide a simple and efficient means for regulating the tension of the computing web.

With these and other objects in view, this invention resides in the novel features of construction, formation, combination and arrangement of parts to be hereinafter more fully described, claimed and illustrated in the accompanying drawing, in which:

Figure 1 is a plan view of the device. Fig. 2 is an end view. Fig. 3 is a bottom plan view of the device. Fig. 4 is a sectional view on line 4—4 of Fig. 1. Fig. 5 is a similar view on line 5—5 of Fig. 1. Fig. 6 is a perspective view of the tension regulator.

Referring to the drawing, the numeral 1 designates a casing having the elongated ends 2, and a bottom 3, the side edges of which are curved inwardly so as to provide a slot 4. It will be of course understood that the bottom 4 and its curved side edges are suitably connected to the ends 2.

Rotatably supported within the casing 1 and having their opposite ends journaled in the ends 2 are spindles 5, said spindles having one of their ends provided with milled heads 6 to facilitate the rotation of the spindles and thus the cylinders 7, which are fixed to the spindles.

The computing web 8 has its side edges secured to the cylinders 7 in any suitable manner, so that when the same is winding upon one cylinder it will unwind from the adjacent cylinder so that the tables 9 print-

ed thereon may be shifted so as to be visual through the slot 4, which is preferably closed by a glass cover 10.

The tension regulator 11 comprises a shaft 12 having a bar 13 threaded upon one end thereof, and a bar 14 loosely connected to the other end, said bars having their opposite ends provided with open slots 15 which are adapted to engage the spindles 5.

A collar X is carried by the rod 12 outwardly of the bar 14, this bar resting thereagainst.

The ends of the bars 13 and 14 are adapted to frictionally engage the opposite ends 70 of the cylinders 7 so that upon rotation of the head 16 the bar 13 may be moved toward or away from the bar 14, thus varying the frictional engagement between the ends of the bars and cylinders, thereby regulating the tension of the web 8.

The tables may be printed so as to compute the price of eggs by the dozen or fraction thereof, and the tables may be printed to indicate the cost of eggs by the crate.

The table illustrated consists of a column of figures from 1 to 40 inclusive, which is preferably printed in red ink and indicates the number of dozens, and an adjacent column of figures from 15 to 600 which indicates the price per dozen. Parallel with the column just mentioned is a column indicating the cost of a dozen eggs or fraction thereof. For example 24 dozen and $\frac{1}{2}$ of a dozen eggs are purchased at 15 cents per dozen, thus totaling \$3.60 added to which is the cost of $\frac{1}{2}$ of a dozen at 15 cents per dozen, which is 12 cents, thus making a total of \$3.72.

The bottom 3 has connected thereto an eye 17 so that the device may be suspended upon a nail so as to position the device vertically, or if desired the same may be arranged at an incline upon a table or desk by the wire support 18 which is pivotally connected to the bottom 3.

What is claimed is:

A device of the class described comprising a casing, spindles journaled at their ends in the ends of the casing and lying in parallel spaced relation, rollers fixed upon the spindles within the casing and terminating short of the ends of the casing, a web mounted on the rollers and arranged to be wound from one to the other, bars located between the ends of the rollers and the adjacent ends of the casing, said bars having

their ends bifurcated and disposed with their furcations at opposite sides of the spindles, a rod loosely engaged through one of the bars and threaded through the other bar, said bar lying between the rollers and a collar carried by the rod outwardly of the bar through which it is loosely engaged, whereby, when the rod is rotated in one di-

rection, the bars will be compressed against the ends of the rollers.

10

In testimony whereof, I affix my signature, in the presence of two witnesses.

EDWARD E. JENKINS.
